PAGE 2

FIG. 4

FIG. 6

FIG. 3

FIG. 5

FIG. 1 is a top plan view of a medicine tray embodying this design.

FIG. 2 is a front elevational view.

FIG. 3 is a side elevational view with portions broken away for convenience of illustration.

FIG. 4 is a vertical sectional view on an enlarged scale taken along line 4—4 of FIG. 1.

FIG. 5 is a bottom plan view.

FIG. 6 is a fragmentary perspective view on an enlarged scale of the lower left corner as seen in FIG. 1.

I claim:

The ornamental design for a medicine tray, substantially as shown.
